UNITED STATES PATENT OFFICE.

JOSEPH KINDL, OF GLEN ULLIN, NORTH DAKOTA.

CULTIVATOR.

1,034,624.

Specification of Letters Patent.

Patented Aug. 6, 1912.

Application filed December 16, 1911. Serial No. 666,160.

To all whom it may concern:

Be it known that I, JOSEPH KINDL, a citizen of the United States, residing at Glen Ullin, in the county of Morton and State of North Dakota, have invented certain new and useful Improvements in Cultivators, of which the following is a specification, reference being had to the accompanying drawings.

10. This invention relates to agricultural apparatus and more particularly to improvements in plows and the like and has for its object to provide means for suitably breaking up the soil dug up by a plow or cultivator.

Another object of this invention is to have the parts of this device adjustable to suit all the conditions arising.

20. A further object of this invention is to have the various parts readily accessible for inspection and repair and of a construction to permit it to be quickly installed on an ordinary plow without interfering with the present arrangement of its parts.

25. Other objects of this invention will become apparent as it is more fully set forth.

In the accompanying drawings which illustrate, by way of example an embodiment of this invention, Figure 1 represents 30 a view in perspective of a plow provided with a device embodying this invention. Fig. 2 is a detail of the frame used in connection with knives for the purpose of breaking up the soil dug up by the same. Fig. 3 is a detail of a mechanism used for 35 adjusting the plow in various positions so that its plow point will dig suitably into the ground; and Fig. 4 is a detail perspective view of a plurality of knife holders and 40 securing plates. Fig. 5 is a detail view showing the construction of the knives.

Similar reference characters refer to similar parts throughout the drawings.

In the appended drawings, 1 represents a 45 plow beam of usual construction which has its front portion 2 slotted to permit an adjustable rack 3 to move freely therein. Fas- 50 tened to the side of the plow beam 1 is a lever and link mechanism 4 arranged to suitably actuate a pair of pawls 5 and 6, which are arranged to engage between the teeth 7 of the rack and hold the latter in various positions, so that the front portion of the 55 plow will be tipped at the most desirable angle for the work in question. Means are provided for raising the rack 3 comprising

a lever 17 pivotally mounted on the stand- 60 ard 18.

A flat metallic V shaped frame 8 having upwardly bent end portions 9 provided with longitudinally disposed slots 10 is secured to one side of the plow beam. To brace the frame and hold it steady I provide an angular member 11 having a longitudinally disposed slot 12 in one of its arms. The other 65 arm of this member is secured to the apex of the frame 8 while the first mentioned arm is fastened to the plow beam on the opposite side from that carrying the frame. The slots 9 and 11 are adapted to receive 70 securing members and permit vertical adjustment of the frame.

Disposed on the frame 8 are a suitable number of knife holders 13, which are secured thereto by means of bolts 14, as is 75 clearly shown in the drawings, and which have their shank portions downwardly extended and provided with holes 15 therein so as to permit the knife points 16 to be held securely thereto. The knife points 16 are 80 disposed at an angle to their shank 16' for a reason to be hereinafter stated.

Securing plates 20 are formed integrally with the top of the holders 13 and bent at right angles to the shank portions so as to 85 lie in a plane parallel to but above the top edges 21 of the holders. The securing plates are of greater width than the thickness of the holders and have a side edge in the same vertical plane as one face of the 90 holders. Bolt holes 22 pass transversely through the securing plates 20 and receive the bolts 14, which fasten the holders to the frame 8. The structure of the holders is such as to permit them to be arranged in 95 overlapped relationship on the frame 8. Each securing plate rests upon the top edge 21 of the following holder 13, which arrangement is very advantageous in that it serves to brace the holders and also to se- 100 cure them more firmly to the frame. This arrangement is clearly shown in Fig. 4. Since the faces of the holders 13 lie in a plane parallel to the front arm of the frame 8, it is necessary, in order that the knives cut 105 properly to have them disposed at an angle to their shanks 16', as shown in Fig. 5. This arrangement causes the cutting edges of the knives to lie in the line of draft, so that they will effectually accomplish the 110 work intended.

The adjustability of the frame 8 enables

the various knives to be disposed on the plow points suitable to the work in question. This adjustment is made by loosening the bolts of various parts of the frame to the 5 beam, and adjusting the latter, after which the bolts are tightened again so that the frame will be held securely in position.

Having thus described this invention, what is claimed is:—

- 10 1. In a cultivator attachment, the combination with a V shaped frame secured to the plow beam, of a plurality of knife holders having downwardly extending shank portions to which the knives are attached, and
- 15 provided with securing plates formed integrally with the top edges thereof and bent at right angles to the aforementioned shank portions, so as to lie in a plane parallel with but above the said top edges, said securing
- 20 plates being of a greater width than the thickness of the holders, said holders being arranged in overlapped relationship on the front arm of the frame.

2. In a cultivator, the combination with a V shaped frame secured to the plow beam, 25 of a plurality of downwardly extending knife holders having their faces alined with the front arm of the V shaped frame, the holders being provided with securing plates formed integrally with the top edges thereof and disposed in a plane parallel to but above the same, the securing plates being of greater width than the thickness of the holders and having a side edge in the same vertical plane as one face of the holders, said securing plates being arranged in overlapped relationship on the front arm of the frame, and knives secured to said holders and twisted to bring their cutting edges in the 30 line of draft.

In testimony whereof I hereunto affix my signature in the presence of two witnesses.

JOSEPH KINDL.
